Primary Examiner — Natasha Vujcic(74) *Attorney, Agent, or Firm* — Weide & Miller, Ltd.(57) **CLAIM**

The ornamental design for an internal lighting fixture, as shown and described.

DESCRIPTION

FIG. 1 is a front view of an internal lighting fixture showing the new design.

FIG. 2 is a rear view of the internal lighting fixture of FIG. 1.

FIG. 3 is a top view of the internal lighting fixture of FIG. 1.

FIG. 4 is a bottom view of the internal lighting fixture of FIG. 1.

FIG. 5 is a right-side view of the internal lighting fixture of FIG. 1.

FIG. 6 is a left-side view of the internal lighting fixture of FIG. 1; and,

FIG. 7 is a perspective view of the internal lighting fixture of FIG. 1.

The broken lines indicate unclaimed portions of the article and form no part of the claimed design.

1 Claim, 4 Drawing Sheets---
